CLAIM

The ornamental design for a display screen or portion thereof with graphical user interface, as shown and described.

DESCRIPTION

FIG. 1 is a front view of a display screen with graphical user interface showing the new design;

FIG. 2 is an enlarged view of the portion referenced as 2 in FIG. 1; and,

FIG. 3 is an enlarged view of the portion referenced as 3 in FIG. 1.

The broken lines showing an electronic device illustrate environmental subject matter and form no part of the claimed design. The broken lines showing a display screen with graphical user interface illustrate portions of the article and form no part of the claimed design. The broken line circles indicate where the enlarged views have been taken and form no part of the claimed design.

1 Claim, 3 Drawing Sheets
